Primary Examiner—Susan Moon Lee*(74) Attorney, Agent, or Firm*—Ostrolenk Faber LLP(57) **CLAIM**

We claim the ornamental design for an image scanner, as shown.

DESCRIPTION

FIG. 1 is a front view of the image scanner embodying our new design;

FIG. 2 is a top plan view thereof;

FIG. 3 is a right side view thereof;

FIG. 4 is a left side view thereof;

FIG. 5 is a rear view thereof;

FIG. 6 is a bottom side view thereof;

FIG. 7 is a first perspective view thereof;

FIG. 8 is a second perspective view of the image scanner with the arm shown in a folded position to be stored;

FIG. 9 is a third perspective view of the image scanner with the camera head shown facing the front of the table; and,

FIG. 10 is a fourth perspective view of the image scanner with the camera head shown facing the rear of the table.
